Primary Examiner — Clare E Heflin(74) *Attorney, Agent, or Firm* — The Belles Group, P.C.(57) **CLAIM**

We claim the ornamental design for a light fixture, as shown and described.

DESCRIPTION

FIG. 1 is a perspective view of the claimed design;
FIG. 2 is a front view of the claimed design shown in FIG. 1;
FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The broken lines shown on the drawings depict portions of the light fixture that form no part of the claimed design.

1 Claim, 6 Drawing Sheets(56)
